CLAIM

The ornamental design for a blender, as shown and described.

DESCRIPTION

FIG. 1 is a top front perspective view of a blender with a combined blender base, blender pitcher container, and container lid in accordance with an embodiment of the present invention;

FIG. 2 is a bottom perspective view of the combined blender base, blender pitcher container, and container lid of FIG. 1; FIG. 3 is a front view of the blender with a combined blender base, blender pitcher container, and container lid of FIG. 1; FIG. 4 is a rear view of the blender with a combined blender base, blender pitcher container, and container lid of FIG. 1; FIG. 5 is a left side view of the blender with a combined blender base, blender pitcher container, and container lid of FIG. 1;

FIG. 6 is a right side view of the blender with a combined blender base, blender pitcher container, and container lid of FIG. 1;

FIG. 7 is a top view of the blender with a combined blender base, blender pitcher container, and container lid of FIG. 1; FIG. 8 is a bottom view of the blender with a combined blender base, blender pitcher container, and container lid of FIG. 1;

FIG. 9 is a front perspective view of the blender base of FIG. 1;

FIG. 10 is a bottom perspective view of the blender base of FIG. 1;

FIG. 11 is a front view of the blender base of FIG. 1;

FIG. 12 is a rear view of the blender base of FIG. 1;

FIG. 13 is a left side view of the blender base of FIG. 1;

FIG. 14 is a right side view of the blender base of FIG. 1;

FIG. 15 is a top view of the blender base of FIG. 1;

FIG. 16 is a bottom view of the blender base of FIG. 1;

FIG. 17 is a front perspective view of the blender pitcher container and container lid of FIG. 1;

FIG. 18 is a bottom perspective view of the blender pitcher container and container lid of FIG. 1;

FIG. 19 is a front view of the blender pitcher container and container lid of FIG. 1;

FIG. 20 is a rear view of the blender pitcher container and container lid of FIG. 1;

FIG. 21 is a left side view of the blender pitcher container and container lid of FIG. 1;

FIG. 22 is a right side view of the blender pitcher container and container lid of FIG. 1;

FIG. 23 is a top view of the blender pitcher container and container lid of FIG. 1; and,

FIG. 24 is a bottom view of the blender pitcher container and container lid of FIG. 1.

(Continued)

Any broken lines, shown throughout in the drawing figures, are included for the purpose of illustrating environmental structures and form no part of the claimed design.
